(57) **CLAIM**

The ornamental design for a tire tread, as shown and
described.

DESCRIPTION

FIG. 1 is a perspective view of a tire tread showing our new
design, it being understood that a tread pattern is repeated
over the outer circumference of the tread width and the
adjacent shoulders of the tire, the opposite side perspective
view being identical thereto; and,

FIG. 2 is an enlarged fragmentary front elevation view of the
tread pattern of FIG. 1.

In the drawings, the dark stippled surface shading represents
the recessed portion of the tread grooves having a depth as
best shown along the right edge of FIG. 1. The broken line
disclosure of a tire sidewall and inner bead are for illustrative
purposes only and form no part of the claimed design.
